Inventor:

George M. Kenney
By Rosario E. Bellone
Atty.

UNITED STATES PATENT OFFICE.

GEORGE M. KENNEY, OF CRANSTON, RHODE ISLAND, ASSIGNOR TO KENNEY MANUFACTURING COMPANY, A CORPORATION OF RHODE ISLAND.

CURTAIN FIXTURE.

Application filed December 21, 1925. Serial No. 76,615.

To all whom it may concern:

Be it known that I, GEORGE M. KENNEY, a citizen of the United States, residing at Cranston, in the county of Providence and State of Rhode Island, have invented certain new and useful Improvements in Curtain Fixtures, of which the following is a specification.

My invention relates to brackets adapted for supporting curtain rods, whether solid, tubular, cylindrical, or flanged.

The essential objects of my invention are to provide a bracket for use intermediate a plurality of windows that are in planes at angles to each other or otherwise; to render the bracket adaptable to use in corners of various degrees of divergence, and to maintain a uniform length of support regardless of the degree of angular divergence; to enable bridging of any spaces that may occur between adjacent window casings; to minimize the number of wall supports; to prevent substantial spaces between the adjacent ends of the supported curtain rods; and to attain these results in a simple and inexpensive structure.

My invention consists primarily in mounting a curtain or drapery rod supporting member on a centrally located bridge plate, to the opposite edges of which attaching plates are yieldingly or pivotally connected. Further invention consists in embodying in a curtain rod supporting member diverging arms for engaging the curtain rods.

In the accompanying drawings which form a part of this specification—

Figures 1 and 2 are a front and a side elevation respectively of a bracket embodying my invention,

Figure 3, a section of the same on line 3—3 of Figure 1,

Figure 4, a modified form of my invention,

Figure 5, a plan view of my brackets supporting curtain or drapery rods in a bay,

Figure 6, a similar view of the same upon a nonangular wall,

Figure 7, a fragmentary front elevation of the end portions of curtain rods mounted on my bracket,

Figure 8, a section of one of the rods on line 8—8 of Figure 7,

Figure 9, a fragmentary plan view of a curved rod end mounted upon another type of bracket, and

Figure 10, a section on line 10—10 of 55 Figure 9.

Like reference characters indicate like parts throughout the views.

My bracket comprises a central base plate or bridge plate 13 provided with lateral hinge sleeves 14 engaging similar sleeves 15 upon hinge leaves or plates 16 provided with openings 17 to accommodate attaching screws. Fixed in the plate 13 is a curtain rod supporting member consisting of a horizontal post 22 fast to whose outer end are branching horizontal lateral arms 24 having upturned flanges 25 upon their outer ends.

My brackets may be employed, as shown in Figure 5, wherein 27 are the frames, or 70 the walls adjacent to, the windows 28; the walls being arranged at angles to each other as in a bay. The bases 13 of the brackets bridge the angles of the frames or wall, and the hinge plates 16 are attached by screws 75 29 to the adjacent portions of the frames, the screws being shown in Figure 7. The posts 22 bisect the angles formed by the frames but, since they are secured in the bases rather than in the frames, the fingers 80

carried by both posts 22 substantially are equidistant from the frames. This insures that the rods carried by the fingers will always be substantially parallel with their corresponding frames. In Figure 5 is 85 shown a central straight telescoping sectional flanged tubular rod 30 having near its ends the usual upper and loosely lower perforations 32 adapted to receive one of each of the two pair of bracket fingers 25. The 90 rod rests upon the arms 24, and is shown further in Figures 7 and 8. In Figure 5 are also shown the side telescoping sectional flanged tubular rods 34 having their end portions inwardly bent as at 35 and provided with top and bottom perforations 36

near their outer ends. Their inner ends have perforations 38 to receive the second of the finger couplets 25 as shown in Figure 7. The brackets for suspending the bent end 100 portions 35 of these rods may be of any form best adapted for this purpose. In the present instance such end brackets, as shown in Figures 9 and 10, comprise attaching plates 40 to which are fixed vertical hooks comprising horizontal portions 41 and vertical beaks 42.

In Figure 6 my novel brackets are shown

employed upon a wall or window frames 44 in the same plane.

It is evident that a plurality of members 24, 25, may be employed upon each rod 22 5 when a series of rods are to be employed. In which case it is obvious that the number of hooks 41 will be increased to correspond.

Attention has hereinabove been called to the parallelism of the rods with the window 10 frames by the hinged relation of the plates carrying the posts of my novel brackets. It is also apparent that the hinged plates are adapted to wall or frame angles of any degree, and that the branched character of the 15 arms of my brackets make it unnecessary to use two separate supporting brackets at the adjacent ends of each set of curtain rods.

The branching arm construction of my bracket also brings the ends of the curtain 20 rods into such close juxtaposition at their angular junction that when drapery is mounted upon the rods the drapery appears continuous.

I claim:—

- 25 1. In a curtain rod bracket, a base plate, plates attached to the sides of the base plate, and movable at an angle thereto, a post upon the base plate, and laterally disposed curtain rod supporting arms upon the post.
- 30 2. In a curtain rod bracket, a base plate, attaching plates pivotally attached to the base plate, a post fast to the base plate, arms upon the post disposed oppositely to each other, and fingers upon the arms.

3. In a curtain rod bracket, a central base 35 plate, attaching plates pivotally hinged to the sides of the base plate, a post rigidly fixed to the base plate at right angles to the plane therof, branch arms fast to the post, and upturned fingers upon the arms. 40

4. In a curtain rod bracket, a base plate, hinge sleeves on the sides of the plate, attaching plates, hinge sleeves on the attaching plates, pintles embraced by the sleeves upon the base plate and attaching plates, a 45 horizontal post on the base plate at right angles to the base plate, oppositely disposed arms carried by the post, a vertical finger upon the arms, said arms and finger being disposed in a plane parallel with the plane 50 of the base plate.

5. The combination in a curtain fixture of a central rod provided with transverse perforations in its ends, of side rods provided with transverse perforations in its ends, 55 base plates, attaching plates hingedly connected to the sides of the base plates, horizontal posts upon the base plates, oppositely directed pairs of arms upon the posts, and vertical fingers upon the arms, the fingers, 60 one finger of each pair entering the perforations in one end of the central rod, and the other finger of the pair entering the perforation in the ends of the side rods adjacent the central rod. 65

In testimony whereof I have affixed my signature.

GEORGE M. KENNEY.
